UNITED STATES PATENT OFFICE

WALTER HOUGHTON WALKER, OF NEW YORK, N. Y., ASSIGNOR TO OTTAWA RIVER PAPER COMPANY, OF TOLEDO, OHIO, A CORPORATION OF OHIO

DISPLAY DEVICE

Application filed March 20, 1933. Serial No. 661,736.

This invention relates to a display device, which includes a stand in the form of a seat, and an insert adapted to be mounted therein.

The general object of the invention is to provide a neat, attractive and inexpensive medium for the display of merchandise for sale. The seat is provided adjacent its back with a slideway. The insert or liner has a back adapted to be inserted in said slideway, and a bottom adapted to rest upon the bottom of the seat and provided with flaps adapted to be folded and held by the sides and bottom of the seat to form a tray for receiving articles in bulk. In the preferred form of the invention, the back of the insert is adapted to be folded in such a manner as to form a ledge for an orderly display of articles.

The invention will be more specifically described in connection with the accompanying drawings, in which—

Figure 1 is a plan view of a blank from which the insert is formed;

Figure 2 is a perspective view of the seat adapted to receive the insert;

Figure 3 is a perspective view of the insert partially folded to the position which it occupies in the completed device;

Figure 4 is a perspective view of the display device completed;

Figure 5 is a horizontal section taken on a plane above the tray in Figure 4;

Figure 6 is a perspective view of an inside corner of the tray.

The seat with which the invention is associated comprises side walls 10, a front wall 11 and a back 12. The upper part of the front wall is folded rearwardly to form the bottom 13 of the seat and fold lines 14 may be provided to facilitate such folding. The front upper portions of the side walls are folded inwardly, as shown at 15, to support the sides of the bottom 13.

The insert or liner comprises a bottom panel 16 and a back panel 17. The rear edges of the side portion 15 of the seat are cut away to form a slideway 18 for receiving the back panel 17 of the insert. The ends of the panel 17 project slightly beyond the edges of the bottom panel 16, as shown at 19, so that as

the panel 17 is inserted in the slideway 18, the sides of the bottom panel 16 fit against the side portions 15 of the seat.

A strip 20 is connected to the bottom panel 16 and is adapted to be folded upwardly about the line 21 to form the front rim of a tray, and a strip 22, connected to the strip 20 at the fold line 23, is adapted to be folded downwardly to form an inner facing for the rim 20.

The insert or liner is provided with two side flaps, each of which comprises a central strip 24 and flaps 25 and 26 connected thereto at the fold lines 27. The strip 24 is a continuation of the strip 20 and is connected thereto at the fold line 28, which is preferably reinforced by a piece of tape 29 or the like.

In forming the tray, after the back 17 has been inserted in the slideway 18, the strip 20 is folded upwardly, as shown in Figure 3, the strip 22 and the flaps 25 and 26 are folded rearwardly and then inwardly about the lines 28. As the bottom of the insert is seated upon the bottom 13, the front rim 20 of the tray and the side flaps 24 are locked in position by the engagement of the latter with the sides 15. The inner facings 22 and 25 of the tray are then folded downwardly to complete the tray. Notches 30 are provided between the strips 22 and 25 and form interlocking tongues 31 for retaining the rim of the tray in this position.

The tray thus formed is adapted to receive merchandise in bulk and is intended primarily for a self-serving display.

It is also desirable to provide the back 17 with fold lines 32, 33 and 34 so that the strips 35, 36 and 37 may be arranged in the position shown in Figures 3 and 4. For this purpose the strips 35 and 36 are cut short enough to permit them to fit between the sides 15, while the ends of the strip 37 are held in the slideway 18. Thus the strip 36 forms a ledge on which an orderly display of articles may be arranged.

It will be understood that the exposed surfaces of the stand may be printed with suitable advertising matter.

From the foregoing description, it will be seen that I have provided a convenient and

inexpensive display device which may be easily set up and which is self-locking. While I have shown and described in detail the preferred form of the invention, it is apparent 5 that the same may be considerably modified without any material departure from the scope of the appended claims.

What I claim is:—

1. The combination with a seat having a 10 bottom, a back and sides, of an insert having a bottom adapted to overlie the seat bottom, a front strip connected to the front edge of the insert bottom and foldable upwardly to form the front rim of a tray, side strips connected to the ends of said front strip and foldable to extend within the sides of the seat to form sides for the tray, and flaps extending inwardly from said side strips and foldable into a position underneath the insert 20 bottom to hold said front and side strips in such folded position.
2. The combination with a seat having a bottom, a back and sides, of an insert having a bottom adapted to overlie the seat bottom, a front strip connected to the front edge of the insert bottom and foldable upwardly to form the front rim of a tray, side strips connected to the ends of said front strip and foldable to extend within the sides of the seat 30 to form sides for the tray, flaps extending inwardly from said side strips and foldable into a position underneath the insert bottom, strips connected to said front and side strips and foldable downwardly to form an inner 40 facing for the tray rim, and means for interlocking said facing strips.
3. The combination with a seat having a bottom, a back and sides, of an insert having a tray bottom adapted to overlie the seat bottom, strips connected to the edges of the insert bottom and foldable to form a rim about the front and sides of the tray bottom, strips connected to said front and side strips and foldable downwardly to form inner facings 50 therefor, and means for interlocking the facing strips.
4. The combination with a seat having a bottom, a back and sides, of an insert having a bottom adapted to overlie the seat bottom, a front strip connected to the front edge of the insert bottom and foldable upwardly to form the front rim of a tray, side strips connected to the ends of said front strip and foldable to extend within the sides of the seat to form 60 sides for the tray, flaps extending inwardly from said side strips and foldable into a position underneath the insert bottom to hold said front and side strips in such folded position, and interengaging means between the seat and the insert back to prevent the insert bottom for slipping forwardly.
5. The combination with a seat having a bottom, a back and sides, of an insert having a bottom adapted to overlie the seat bottom, a front strip connected to the front edge of

the insert bottom and foldable upwardly to form the front rim of a tray, side strips connected to the ends of said front strip and foldable to extend within the sides of the seat to form sides for the tray, flaps extending inwardly from said side strips and foldable into a position underneath the insert bottom, strips connected to said front and side strips and foldable downwardly to form an inner 70 facing for the tray rim, means for interlocking said facing strips, and interengaging means between the seat and the insert back to prevent the insert bottom from slipping forwardly.

6. The combination with a seat having a bottom, a back and sides, of an insert having a tray bottom adapted to overlie the seat bottom, strips connected to the edges of the insert bottom and foldable to form a rim about the front and sides of the tray bottom, strips connected to said front and side strips and foldable downwardly to form inner facings therefor, means for interlocking the facing strips, and interengaging means between the seat and the insert back to prevent the insert bottom from slipping forwardly. 80

7. The combination with a seat having a bottom, a back and sides, of an insert having a bottom and a back adapted to overlie the bottom and back of the seat, a vertical slideway at the back of the seat for receiving the back of the insert, a front strip connected to the front edge of the insert bottom and foldable upwardly to form the front rim of a tray, side strips connected to the ends of said front strip and foldable to extend within the sides of the seat to form sides for the tray, and flaps extending inwardly from said strips and foldable into a position underneath the insert bottom to hold said front and side strips in such folded position. 90

8. The combination with a seat having a bottom, a back and sides, of an insert having a bottom and a back adapted to overlie the bottom and back of the seat, a vertical slideway at the back of the seat for receiving the back of the insert, a front strip connected to the front edge of the insert bottom and foldable upwardly to form the front rim of a tray, side strips connected to the ends of said front strip and foldable to extend within the sides of the seat to form sides for the tray, flaps extending inwardly from said side strips and foldable into a position underneath the insert bottom, strips connected to said front and side strips and foldable downwardly to form an inner facing for the tray rim, and means for interlocking said facing strips. 100

9. The combination with a seat having a bottom, a back and sides, of an insert having a tray bottom adapted to overlie the bottom of the seat and having a back adapted to overlie the back of the seat, a vertical slideway at the back of the seat for receiving the back of the insert, a front strip connected to the 110

front edge of the insert bottom and foldable upwardly to form the rim of the tray bottom, strips connected to said front and side strips and foldable downwardly to form inner facings therefor, and means for interlocking the facing strips.

10. The combination with a seat having a bottom, a back and sides, said sides being provided adjacent the back with opposed channels constituting a vertical slideway, of an insert having a bottom and a back adapted to overlie the bottom and back of the seat, the back of said insert comprising upper and lower strips, with their ends guided in said 15 slideway, and intermediate strips trimmed short enough to swing forwardly between the sides of the seat to form a ledge, all of said strips being arranged successively one

above the other and connected by fold lines.

11. The combination with a seat having a bottom, a back and sides, said sides being provided adjacent the back with opposed channels constituting a vertical slideway, of an insert having a bottom and a back adapted to overlie the bottom and back of the seat, the back of said insert comprising upper and lower strips, with their ends guided in said slideway, and intermediate strips trimmed 75 short enough to swing forwardly between the sides of the seat, the upper one of said intermediate strips being narrower than the lower intermediate strip.

In testimony whereof I have hereunto 80 signed my name to this specification.

WALTER HOUGHTON WALKER.
